(57) **CLAIM**

The ornamental design for a multifunction electronic device, as shown and described.

DESCRIPTION

FIG. 1 is a perspective view of a multifunction electronic device in accordance with the new design;

FIG. 2 is a top plan view thereof;

FIG. 3 is a right side view thereof;

FIG. 4 is a bottom view thereof;

FIG. 5 is a left side view thereof;

FIG. 6 is a rear view thereof; and,

FIG. 7 is a front view thereof.

The broken lines shown in FIGS. 1, 2, 4, and 6-7 are for the purpose of illustrating portions of the multifunction electronic device that form no part of the claimed design.
